UNITED STATES PATENT OFFICE.

ANDREW R. WINGARD AND GUNNAR WINGARD, OF TACOMA, WASHINGTON.

REFRIGERATED DISPLAY CASE.

Application filed March 31, 1922. Serial No. 548,468.

To all whom it may concern:

Be it known that ANDREW RICHARD WINGARD and GUNNAR WINGARD, citizens of the United States, and residents of Washington, in the city of Tacoma and county of Pierce, have invented certain new and useful Improvements in Refrigerated Display Cases, of which the following is a specification.

10 The primary purpose of the present invention is to effect a continuous circulation of cool air within a counter or case of the display type, to the end that meat or any other perishable products displayed within 15 the case may be kept fresh and in good condition.

Another purpose of the invention is to insure circulation of air to all parts of the interior of the case by directing the air currents in opposite directions from a central point in the case to the opposite ends thereof.

Another purpose of the invention is to provide an economical and efficient display case structure, wherein the cooling medium 25 and the housing containing the same are located exteriorly of the display case proper, and connected therewith by suitable air passages to provide for the necessary circulation of cooled air.

30 Other objects of the invention, as well as the particular combination, construction and arrangement of parts comprising the same, will be more readily understood from the following description and accompanying 35 drawings.

In the drawings:

Fig. 1 is a perspective view of a display case constructed in accordance with our invention.

40 Fig. 2 is an end view with portions of the display case and cooling chamber removed to disclose interior construction.

Fig. 3 is a perspective view of a modification and;

45 Fig. 4 is a perspective view of the cooling coil.

Referring to the drawings by numerals, and more particularly to the form of invention illustrated in Figs. 1 and 2, numeral 50 5 designates a substantially rectangular base member forming the bottom wall of a display case 6. The case 6 is preferably provided with transparent front and end walls 7 and 8, and non-transparent top and rear 55 walls 9 and 10, the rear wall 10 being preferably constructed to provide either hinged

or sliding closures of conventional type through which access may be obtained to the interior of the case.

An air cooling chamber, designated by 60 the numeral 11, is supported on the top wall 9 at a point intermediate the ends of the case and may be constructed as a substantially integral part of said top wall or as an attachment thereto. This chamber affords 65 a housing for a cooling coil 12 having an inlet 13 and an outlet 14 depending downwardly into the case 6 and passing outwardly through the base member 5 for connection with any suitable refrigerant circu- 70 lating system.

A continuous circulation of cool air between the cooling chamber 11 and the case 6 is afforded through the medium of the air flues or passages designated, respectively, 75 by the numerals 15, 16 and 17. The central air flue or passage 16 serves to conduct cooled air from the chamber 11 into the case 6 and consists preferably of a rectangular casing 16 depending from the cooling

80 chamber into the display case and terminating a short distance above the base member 5. It will thus be seen that the air passing through this flue is discharged into the case 6 at a substantially central point there- 85 in and passes, in oppositely moving currents, toward the ends of the case. The heated air arising at the ends of the case is deflected inwardly by the top wall 9 and flows toward the central portion of the case, being returned to the chamber 11 through the passages 15 and 17. These latter passages 90 are formed by the provision of deflecting plates 18 located within the chamber 11 on opposite sides of the flue 16 and in spaced relation with the end walls of the chamber. The lower ends of these deflectors 18 are extended downwardly into the display case and directed toward the ends of the latter, as at 19, so as to have a scoop-like 100 effect on the currents of air impinging thereagainst to more readily direct such air into the cooling chamber.

As shown to advantage in Fig. 2, the base member 5 is approximately twice the width of the case 6 and projects a considerable distance beyond the rear wall of the latter to afford a shelf 20, which may be provided at its ends with vertical walls 21. At a suitable point, preferably opposite the cooling chamber 16, the shelf 20 has secured thereon, a platform 22 which serves to support a 105 110

weighing scale 23 having the indicating portion 24 thereof projecting above the top of the cooling chamber so as to be visible from in front of the case.

5 In the modification disclosed in Fig. 3, the cooling chamber designated 6^a is supported in slightly elevated position above the top wall 9 of the case, by means of the depending flues 7^a, 8^a and 9^a. In this form 10 of the invention, the central flue 8^a is extended downwardly through an opening in the top of the case to a point in proximity to the bottom wall of the case. The end flues 7^a and 9^a have only the inner walls thereof extended 15 downwardly into the interior of the case, these walls being directed toward the ends of the case to serve as air scoops for deflecting heated air into the chamber 6^a. The upper edges of the flues 7^a and 9^a are extended 20 upwardly within the cooling chamber 6^a in spaced relation with the end walls of the chamber to terminate slightly below the top wall of the chamber, whereby air entering these flues will be carried to the extreme top 25 of the cooling chamber before coming in contact with the cooling coil 12. Also, in this form of the invention, the inlet and outlet portions of the cooling coil may be extended outwardly through the rear wall of 30 the cooling chamber instead of being carried downwardly through the display case as described in connection with the previous figures.

It will be understood that our invention 35 contemplates the use of any suitable cooling coil, but preferably, we make use in this connection of a single length of pipe bent to present a plurality of substantially parallel rectangular coils 12^a as shown to advantage 40 in Fig. 4.

From the foregoing, it will be apparent that we have provided an efficient, economical and extremely simple type of refrigerating display case which is particularly adapted 45 to keep fresh and in good condition, such perishable articles as may be displayed therein. In both forms of the invention, the cooled air from the cooling chamber is discharged into the display case at a point intermediate the ends of the latter and in close 50 proximity to the bottom wall thereof, whereby oppositely moving currents of air are set up to pass from the center of the case to the opposite ends thereof, thus insuring an adequate supply of air to all parts of the case.

In the foregoing we have disclosed what we now consider to be the preferred embodiments of our invention, but it is to be understood that we do not desire to limit ourselves to the exact construction, combination 60 and arrangement of parts described, as it is obvious that various modifications could be resorted to within the spirit and scope of the appended claims.

Having thus fully described our invention, what we claim is:

1. The combination with a display case of a superimposed casing, an intermediate flue surrounding a central opening in the bottom of the casing and depending downwardly through the top of the display case to a point adjacent to the bottom of said case, end flues spaced from the intermediate flue and establishing communication between the display case and the 70 end portions of the casing, the inner walls of said end flues being arranged to define an intervening cooling compartment in the casing and being spaced from the top wall of the casing, the lower edges of said 75 end walls being disposed within the display case and inclined in opposite directions to provide integral air deflecting scoops.

2. The combination with a display case presenting a top wall provided with a central inlet opening and with outlet openings arranged on opposite sides of the inlet opening in spaced relation thereto, of a superimposed casing presenting a bottom wall spaced from the top wall of the display case 80 and provided with a central outlet opening opposing the central inlet opening in the display case, an intermediate flue surrounding said central outlet opening and depending downwardly through the central inlet 85 opening in the display case to a point in proximity to the bottom of said case, said casing being further provided with depending end flues extending downwardly through the outlet openings in the display case, the inner walls of said end flues being extended 90 upwardly into the casing to define an intervening cooling compartment and being directed downwardly into the display case and inclined in opposite directions to provide integral air deflecting scoops.

In testimony whereof we hereunto affix our signatures.

A. R. WINGARD.
GUNNAR WINGARD.
